UNITED STATES PATENT OFFICE.

WARREN A. PATTERSON, OF ST. LOUIS, MISSOURI, ASSIGNOR TO AMERICAN COTTON SEPARATOR COMPANY, OF ST. LOUIS, MISSOURI, A CORPORATION OF OKLAHOMA TERRITORY.

COTTON-SEPARATOR.

No. 856,421.

Specification of Letters Patent.

Patented June 11, 1907.

Application filed June 25, 1906. Serial No. 323,296.

To all whom it may concern:

Be it known that I, WARREN A. PATTERSON, a citizen of the United States, residing at St. Louis, Missouri, have invented a certain new and useful Improvement in Cotton-Separators, of which the following is a full, clear, and exact description, such as will enable others skilled in the art to which it appertains to make and use the same, reference being had to the accompanying drawings, forming part of this specification, in which—

Figure 1 is a side elevation of a cotton separator embodying the features of my invention; Fig. 2 is a plan view of the same with the vacuum box removed; Fig. 3 is a vertical longitudinal sectional view through the separator; Fig. 4 is an enlarged detail sectional view showing the construction of the ports and valves employed for controlling the admission of air into the separating chamber; Fig. 5 is a transverse sectional view taken at approximately the line 5—5 of Fig. 2, the vacuum box being shown in this view; Fig. 6 is an enlarged detail sectional view showing a portion of one of the air controlling valves; Fig. 7 is a sectional view on the line 7—7 of Fig. 3; and Fig. 8 is a detail view of one of the members 12.

This invention relates to cotton separators, and the object of my invention is to provide a machine of simple construction which will separate the bolls from the cotton and carry them to different points. To this end I have constructed a machine comprising a separating chamber into which the bolls are fed after they have been broken open, and located in this chamber are a plurality of rotatably toothed members arranged adjacent each other and all rotating in the same direction so that one-half of each member will be carrying the cotton or bolls in one direction while the other half of said member will be co-operating with the member adjacent thereto to strip the bolls from the cotton.

Referring to the drawings which represent the preferred form of my invention, 1 designates the casing of the machine in which the separating mechanism is located, and 2 designates a vacuum box located over an opening 3 at the lefthand end of the casing, as shown in Fig. 3. The vacuum box is preferably of the form shown in the drawings, and leading into an opening in one of the side walls of

said box is a tube 4 having a plurality of rotary beaters 5 mounted therein. A tube 6 communicating with a blower 7, is arranged at the other side of the vacuum box in alignment with the tube 4, as shown in Fig. 5, and a screen 8 is interposed between these two tubes inside of the vacuum box. The bolls, 60 after they have been picked from the field, are drawn through the tube 4 by the suction of the blower 7 and as the bolls pass through this tube 4 they are broken open by the rotary beaters 5, the screen 8 preventing the 65 bolls and cotton from being drawn into the blower 7 so that they drop through the opening 3 onto an endless carrier inside of the casing 1, as shown in Fig. 3. The endless carrier is made up of a plurality of endless belts 70 9 to which cross slats 10 are secured and said carrier travels on a substantially box-shape member 11 extending the full length and width of the casing 1 and acting as a partition to divide the upper portion of the casing 75 into a separating chamber. A plurality of rotating toothed members 12 are mounted in this separating chamber above the endless carrier, each of said members being made up of a number of toothed disks mounted on 80 shafts 13 and spaced apart to permit air to pass between said disks. The members 12 all rotate in the same direction, and means is provided for forcing the broken bolls or portions of bolls into engagement with these rotating members 12 as the bolls are fed into the separating chamber by the endless carrier. The members 12 are arranged quite close to each other, as shown in Fig. 3, and if 85 said members are rotating in the direction indicated by the arrows in Fig. 3 the portions of the members 12 which travel in the plane at the lefthand side of the central line 15 in Fig. 3 will carry the cotton and bolls upwardly toward the top of the casing and the 90 portions of the members 12 which travel in the plane at the righthand side of the central line 15 will engage the bolls and strip them from the cotton, the distance between the members 12 not being great enough to permit the bolls to pass between same.

The means for forcing the bolls and cotton into contact with the members 12 consists of air supplied by a fan or from any suitable source and entering the box 11 through a 105 tube 16 communicating with an opening 17

in one side thereof, as shown in Figs. 1 and 5. The air escapes from the box 11 through ports 18 and 19 in the top of the box and these ports are preferably located under the 5 members 12 and are inclined, as shown in Fig. 3. As shown in the drawings two ports are provided for each of the members in order that the point at which the bolls and cotton engage said members may be varied, 10 valves 20 being provided for controlling said ports as it is generally necessary to utilize only one port for each of the toothed members 12. The valves 20 are slidingly mounted and each valve has a handle 21 that projects through an opening 22 in the side wall 15 of the box and casing, as shown in Fig. 6, the end of the valve being of such size that said opening is always closed no matter what position the valve is in.

20 As previously stated, the toothed disks which comprise the members 12 are spaced apart so that the air which forces the bolls and cotton into engagement with said members can rush to the upper part of the separating chamber and carry the cotton out of the machine through the opening 22^a at the end of the casing, the bolls as they are stripped from the cotton dropping onto the endless carrier which conveys them to the 25 discharge opening 23 at the righthand end of the casing. Preferably, a box 24 is located above the three toothed members 12 at the lefthand end of the separating chamber, as shown in Fig. 3, and the bottom wall of 30 said box is provided with ports 25 and 26 and valves 27 for closing them similar to the ports and valves in the box 11. Air is supplied to this box 24 by means of a conduit 28 which extends from the side of the box 11 35 and enters the top wall of the box 24. The ports in the box 24 are also inclined so that the air passing through said ports will tend to force the cotton from the members 12 and out through the discharge opening at the 40 righthand end of the machine.

45 For preventing the air in the separating chamber from escaping into the vacuum box, a flexible flap 28' is connected to the lefthand end wall 29 of said chamber and lies on the 50 upper surface of the endless carrier, a stripper plate 30 being also connected to said end wall to co-operate with the member 12 adjacent thereto. If desired, the members 12 may be rotated in the opposite direction to that indicated by the arrows 14 in Fig. 3, a stripper 55 31 being arranged at the righthand end of the casing to co-operate with the toothed member 12 adjacent thereto. The endless carrier travels over rollers 32 and 33, the 60 shaft which carries the roller 32 being provided with a pulley 34 which is driven by a belt 35 that passes over a pulley 36 on the main shaft 37, as shown in Fig. 2. The shafts which carry the toothed members 12 are provided with pulleys 38 and 38' with

which belts 39 and 39' co-operate, one of the belts 39' passing over a pulley 40 on the main shaft whereby a continuous rotary movement in the same direction will be imparted to the toothed members 12.

70 While I have herein shown the toothed members 12 and the endless carrier as being driven by belts and pulleys it is obvious that gearing or other actuating mechanism could be used without departing from my invention.

75 Having thus described my invention, what I claim as new and desire to secure by Letters Patent is:

80 1. A machine for separating cotton from bolls comprising a plurality of rotating members arranged adjacent to each other and provided with unyielding teeth, pneumatic means for forcing the bolls and cotton onto said members whereby a portion of the teeth 85 of each member operates to move the cotton in one direction while the other portion of the teeth of said member operates to strip the bolls from the cotton that is being carried by the teeth of the member adjacent thereto; substantially as described.

85 2. A machine for separating cotton from bolls comprising a plurality of members arranged adjacent to each other and provided with rigid teeth that coöperate with each 90 other to strip the bolls from the cotton, means for feeding the bolls adjacent said members, and pneumatic means for forcing the bolls into engagement with the teeth of said members and for removing the separated 95 cotton therefrom; substantially as described.

100 3. A machine for separating cotton from bolls comprising a plurality of rotating members arranged adjacent each other and provided with rigid teeth that coöperate with each other to strip the bolls from the cotton, pneumatic means for feeding the bolls into engagement with the teeth of said members and for conveying the separated cotton out of the machine, and means for conveying the 105 stripped bolls out of the machine; substantially as described.

110 4. In a machine of the character described, a casing having a plurality of rotatable members mounted therein, said members being 115 provided with rigid teeth which coöperate with each other to strip the bolls from the cotton, an air chamber located under said members and provided with air ports through which jets of air are blown for forcing the bolls into engagement with said members, and means for supplying air to 120 said chamber; substantially as described.

125 5. In a machine of the class described, a plurality of members for stripping bolls from cotton, an air chamber located adjacent said members and provided with ports through which jets of air are blown to force the bolls into engagement with said members, means for supplying air to said chamber, and means 130

for controlling the passage of the air through said ports; substantially as described.

6. In a machine of the class described, a plurality of members for stripping bolls from cotton, an air chamber located adjacent said members and provided with inclined ports through which jets of air are blown to force the bolls into engagement with said members, means for supplying air to said chamber, and means for controlling the passage of the air through said ports; substantially as described.

7. In a machine of the class described, a casing having a plurality of members mounted therein for stripping bolls from the cotton incased in said bolls, an air chamber arranged under said members and provided with ports through which jets of air are blown to force the bolls into engagement with said members, an air chamber arranged above some of said members and provided in its bottom wall with ports through which jets of air are blown, and means for supplying air to said chambers; substantially as described.

25 8. In a machine of the class described, a casing having a plurality of rigid toothed members rotatably mounted therein and adapted to coöperate with each other to strip the bolls from the cotton, an air chamber arranged under said members and provided in its top wall with air ports, and a movable conveyer arranged between said members and the air chamber; substantially as described.

35 9. In a machine of the class described, a casing, a plurality of toothed members arranged in said casing and adapted to co-operate with each other to strip the bolls from the cotton, an air chamber arranged below said members and provided with air ports, an air chamber arranged above said members and provided with air ports and a conduit connecting said chambers; substantially as described.

45 10. In a machine of the class described, a casing provided with discharge openings

through which the cotton and the bolls pass, a plurality of rotatable members arranged in said casing and adapted to co-operate with each other to strip the bolls from the cotton 50 which the bolls incase, each of said members consisting of a plurality of toothed disks mounted on a shaft and being spaced away from each other, an air chamber arranged under said members and provided with ports 55 through which jets of air are blown to force the bolls into engagement with said members and also carry the separated cotton through the discharge opening therefor, means for supplying air to said chamber, and a conveyer 60 for carrying the stripped bolls to the discharge opening therefor; substantially as described.

11. In a machine of the class described, means for breaking open cotton bolls, a plurality of members rotating in the same direction and provided with rigid teeth that co-operate with each other to strip the bolls from the cotton, means for conveying the broken bolls to said members, and pneumatic means for forcing said bolls into contact with said members; substantially as described.

12. In a machine of the class described, a vacuum box, a tube communicating with 75 said box and having beaters mounted therein, an endless conveyer traveling under the discharge opening of said vacuum box, a plurality of toothed members arranged above said conveyer and co-operating with each 80 other to strip the bolls from the cotton, said members being constructed to permit air to pass therethrough; substantially as described.

In testimony whereof, I hereunto affix my 85 signature, in the presence of two witnesses, this eighteenth day of June 1906.
